7 Claims. (Cl. 221—7)

ABSTRACT OF THE DISCLOSURE

Individual strands, from a bundle of strands, are independently separated, and optionally counted or fed to a subsequent process, by placing the bundle in a notch above a revolving or reciprocating wheel having grooves of a size to receive the major part of one individual strand, whereby one strand drops into a groove, and is passed under a spring-loaded resilient block, which holds back all other strands. The separated strand is photoelectrically counted, or discharged into the edge of the nip of revolving feed rolls.

Background of the invention

The problem of separating strands from a bundle containing a large number of them and feeding them and/or counting them arises particularly in the case of surgical sutures, which are often produced in bundles which may contain a hundred or more sutures, the sutures often being quite long, for example about five feet. This renders the bundle somewhat awkward to handle. Surgical sutures always have to be counted at some stage and often have to be fed singly to other processing devices, such as for example grinders, in the case of catgut sutures, sorters to sort sutures of different diameters, and the like. Sometimes it is only necessary to count the sutures, as for example in the case where sutures are not to be processed mechanically but are to be separated into smaller bundles of predetermined numbers. It has been the practice in the past, with sutures, to do, by hand, the operations of separating from bundles, feeding into further processing or counting. This presents several drawbacks. First of all, there is the cost of an additional operator. Then, when one relies upon manual operation the output is limited by the rate at which an operator can separate individual sutures from a bundle and feed them into further processing machinery. When counting of sutures is involved, this is hard on the operator's eyes, and the possibility of human error becomes a significant factor, especially if an operator becomes tired. For these and other reasons there has been a demand for a completely accurate, simple and automatic machine for separating and/or counting sutures. Some complicated devices involving reciprocating plungers, air blasts, and the like have been proposed, but they involve considerable complication, and in some cases the accuracy and speed are not all which could be desired.

Summary of the invention

The present invention is directed to an improved machine for separating strands, each strand being held in the separated position reliably and, if desired, counted. Essentially the present invention involves loading a large bundle onto a machine with one or more V notches, which has its bottom or apex covered by a rotating or reciprocating wheel provided with notches or grooves in its periphery, capable of grasping a strand, moving it out from the notch, and transporting it to or through other mechanisms, such as counters, single strand feeders, and the like. The wheel can be very accurately adjusted so that a single strand at a time is picked up, or perhaps more logically picked down, since the wheel removes the strand from the bottom of the notch. A resilient foot at the point

2

of separation insures a single strand being fed, without damage to it or to the strands not yet fed. At the same time, the operation is very fast, being limited only by the other equipment, such as single strand feeders, which may be used with the machine. Another advantage is that the grooves or notches in the periphery of the separating wheel are rounded and polished and the foot is of resilient material and there is, therefore, no danger of injuring the surface of a strand. The danger of injury to the surface of the suture is greater with catgut sutures, which can fray, but is also of concern, although less important, with softer sutures such as braided polyester, nylon, and the like.

While the surgical suture field is the most important single field of utility for the present invention, it should be understood that the machine is not limited thereto and can separate, count or feed strands for any use. As the suture separating and feeding or counting field is the most important and presents the problems solved by the present invention most clearly, the specific description which will follow is for use of the machine with sutures, it being understood, of course, that this is merely a typical illustration and the invention in its broader aspects is not limited thereto.

Brief description of the drawings

FIG. 1 is an isometric view of a machine for separating and feeding surgical sutures, and

FIG. 2 is a similar isometric view of a machine equipped for counting sutures without feeding them to other processing machines.

FIG. 3 is an enlarged front view of part of the machine showing details of the separating mechanism.

FIG. 4 is an enlarged first sequential view showing the wheel with the notch containing a suture approaching the resilient insert.

FIG. 5 is a view showing the wheel with the notch containing a suture after the suture has passed under the resilient block partially lifting the resilient block, as the resilient block prevents other sutures from following.

FIG. 6 is a view showing the wheel with the notch containing a suture as the suture is about to emerge from under the resilient block.

FIG. 7 is a view showing the wheel with the notch containing the suture after it is passed under the resilient block, with the resilient block dropping down against the wheel, and holding back other sutures.

FIG. 8 is a view of the wheel with the now empty groove, as the suture is discharged.

Description of the preferred embodiments

As many of the parts of the machines in the three figures are the same, they will be given the same reference numerals in each figure.

In FIG. 1 there is shown a framework at 1 on which the component parts of the machine are mounted. A bulkhead 2 is provided with a notch 3, one side of which is sloping and the other including a member, which is movable, pivoted about a bolt 8, and provided with a rubber insert 7. At the bottom of the notch there is a wheel 5 provided with a series of round grooves 15. The rubber insert 7 in the movable member 4 is held against the periphery of the wheel by the spring 9. A bundle of sutures 6, for example catgut sutures, is loaded onto the notch 3 and is supported on the top 10 of a compartment 11 containing the motor drives, which being of standard design are not specifically shown. The front of the compartment 11 carries suitable switches, as labeled, and the top 10 is provided with a window 12, behind which there is a counter 21 of conventional design. Loading a bundle of sutures on the machine can be done rapidly when a new bundle is to be counted or fed, the only care required being that the left hand end of the suture bundle

project sufficiently beyond the notch 3 so that a separated suture can be grasped by the wheel 5 cooperating with the rubber insert 7.

Loading suture bundles occurs only at longer intervals as a bundle of sutures may have 100 or more. The loading can be effected manually, as illustrated in the drawings, though of course automatic loading may be provided if desired. Saving by automatic over manual loading is, however, so small that it is normally preferred to load manually. The wheel 5 may be rotated continuously or it may be reciprocated through a sufficient arc to pick up a suture and transfer it down to the discharge point 13. This is shown in the enlarged view, FIG. 3, and sequented views FIGS. 4 to 8. The choice of reciprocation or continuous rotation depends on the use. With counters, only, which will be described in conjunction with FIG. 2, the faster operation with continuous rotation presents some advantages. However, in FIG. 1, where the separated suture is fed to a single strand feeder, which will be described below, a reciprocation has more than adequate speed and has an advantage that the grooves 15 in the wheel 5 may be of different size so that different sizes of sutures can be fed by loosening the lock 14 on the wheel shaft and turning it so that another groove of different size comes into play. As the reciprocating mechanism is of standard design, it is not shown. It is enclosed in the compartment 11.

The dimensions of the grooves 15 are important; more than 50% of the suture must be in the groove for proper separation, and the rubber insert 7 has a sharp leading edge in order to prevent feeding more than one strand at a time. A typical example of groove dimensions for a nominal .020" suture (dimension ranges from .016" to .024"), is .018" deep and .024" wide. Actually, this size of groove could operate with a suture as large as .026".

As the wheel 5 reciprocates, a groove 15 passes along the bottom of the notch 3 picking up a single suture by cooperation with the rubber insert 7. The wheel moves on, carrying the suture underneath the rubber insert to a position shown at 13. While no very serious harm is done if an occasional suture does not fall into a groove when it is passing across the bottom of the notch 3, it is still desirable to prevent this happening, particularly in the modification shown in FIG. 1 where the separated suture is fed on to other equipment. This is easily effected by having many sutures lying at the bottom of notch 3 so that one will always fall into a groove 15 as it passes.

When the wheel 5 is moved to the extreme position and the suture is at 13, it will be seen that it is beneath the member 4 and so is free to move longitudinally. The suture is gripped by a pair of rollers 16 and is fed on through a single strand feeder 17 with an enlarged conical guiding mouth 18. In FIG. 1 this suture is shown as moved by the rollers 16 to the point where it is entering the single strand feeder. The rollers 16 rotate continuously at a predetermined speed suitable for the single strand feeder and their tops are rounded so that as the suture is moved down to the position 13 by the wheel 5 it falls into contact with the turning faces and is driven forward, as has been described. The single strand feeder 17 can feed the suture into any suitable equipment, such as grinding or other processing equipment. The nature of this equipment forms no part of the present invention and is, therefore, not shown.

The rate of reciprocation of the wheel 5 should be adjusted in accordance with the speed of the rollers 16 so that a new strand is brought into contact with the rollers as the proceeding strand leaves them. In general the rate of feed is adjusted by determining the speed of the rollers 16, the reciprocating drive of the wheel 5 being always proportional thereto, through suitable gearing. When a bundle is exhausted or nearly exhausted, the operator can replace another bundle on the device, with or without stopping and starting the machine, as may be desired, depending on the circumstances of use.

FIG. 2 shows a modification for counting sutures, many of the parts being the same as those shown in FIG. 1 and so bearing the same numerals. In this modification wheel 5 turns continuously and so, of course, can be used only with one size of suture. However, loosening of the locking cap 14 permits rapid replacement of the wheel when a new size of suture is to be counted. As the wheel is not reciprocated, a somewhat different counting mechanism is shown, including a lamp 20 and an electric eye or counter 19, which later goes to the counter readout 21. Much faster operation is possible than when the separated strands are to be passed on to other equipment, as shown in FIG. 1, and this may be effected either by turning the wheel 5 faster or providing it with a larger number of grooves 15 or both. It will be noted that since there are no rollers 16 the separated strands form a new bundle and when the desired number has been counted the machine stops, by conventional interconnection of the counter with the starting and stopping switch. The counted bundle is removed and the machine restarted. Instead of stopping the drive to the machine, a clutch can be provided, which is not shown, and the motor may operate continuously.

The counting mechanism may perform the function of keeping an accurate record of the number of sutures fed to other equipment in the modification of FIG. 1, or it may be used to alert an operator that a bundle of sutures is almost exhausted, or it can perform both functions. The alerting function obviously requires contact with suitable alarm, such as a light, when a number of sutures has been counted somewhat less than the normal number in a bundle. This makes it possible for a single operator to monitor more than one machine or more than one operation.

The present invention is a machine and as such is not broadly concerned with the materials of which the machine is formed. However, it is desirable to have the notch 3 with its sides and the wheel 5 of suitable material for the nature of the sutures or other strands which are to be separated. Usually metals are desirable as they do not wear rapidly and can take a high polish. The insert 7 must, of course, be of soft material, but otherwise the choice of materials for the machine is limited only by practical consideration of suitability. The operation of the machine, of course, is not affected by the material of which it is constructed.

I claim:

1. A strand separating machine for separating strands from a bundle comprising in combination:
  - (a) a framework with at least one bundle supporting notch, located adjacent to the end of a bundle of strands and having a grooved separating wheel above the notch apex,
  - (b) the separating wheel having its periphery adjacent to and effectively closing the apex of the notch and being provided with peripheral grooves of dimensions so that a suture is at least 50% in the groove, the wheel having a plurality of widely spaced grooves of different sizes for different sized strands,
  - (c) a soft, resilient member maintained in contact with the wheel periphery and positioned to prevent a suture in the groove from jumping out as the wheel moves,
  - (d) means for reciprocating the wheel through an arc less than the spacing between grooves of different sizes but at least sufficient to move a groove with a strand therein out of contact with the resilient member and to a position where the strand falls out of the groove, and
  - (e) means for bringing grooves of different predetermined sizes into the arc of reciprocation near the bottom of the notch and for holding such grooves during reciprocation of the wheel through the arc.
2. A machine according to claim 1 provided with means for counting each separated strand.

3. A strand separating machine for separating strands from a bundle comprising in combination:

- (a) a framework with an extended bundle supporting means including at least one bundle supporting notch located adjacent to one end of a bundle of strands,
  - (b) a narrow grooved separating wheel above the notch apex the width of the wheel being at least an order of magnitude less than the length of the bundle supporting means,
  - (c) the separating wheel having its periphery adjacent to and effectively closing the apex of the notch and being provided with peripheral grooves of dimensions so that a strand is at least 50% in the groove,
  - (d) a soft resilient member maintained in contact with the wheel periphery and positioned to prevent a strand in the groove from jumping out as the wheel moves,
  - (e) means for moving the wheel through an arc at least sufficient to move a groove with a strand therein out of contact with the resilient member and to a position where the strand falls out of the groove.
4. A machine according to claim 3 in which the wheel is continuously rotated.

5

10

5. A machine according to claim 4 provided with means for counting each separated strand.

6. A machine according to claim 3 comprising means, engaged by a separated strand, for translating said strand axially, whereby the machine separates strands and moves each separated strand axially out of the bundle.

7. A machine according to claim 6 in which the movement of the wheel is a reciprocation over a fraction of a full turn, and timing means to provide one reciprocation during the time required for moving one strand axially by the translating means.
